UNITED STATES PATENT OFFICE.

FLETCHER D. HALLOCK, OF PITTSBURGH, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,186,770.

Specification of Letters Patent. Patented June 13, 1916.

Application filed December 26, 1911. Serial No. 667,918.

To all whom it may concern:

Be it known that I, FLETCHER D. HALLOCK, a citizen of the United States, and a resident of Pittsburgh, in the county of Allegheny and State of Pennsylvania, have invented a new and useful Improvement in Circuit-Interrupters, of which the following is a specification.

My invention relates to electric circuit 10 interrupters and it has for its object to provide a simple and durable device of this character that shall open automatically upon the failure of the voltage or a material reduction in the current in the circuit with 15 which it is associated.

No-voltage release circuit breakers are well known, but, in order to make a particularly simple and inexpensive structure, I employ coöperating magnetizable members which are dependent directly upon the current traversing the circuit for forcibly holding a pair of relatively movable contact members together.

Figure 1 of the accompanying drawing is 25 a partially sectional elevation of a circuit interrupter constructed in accordance with my invention. Fig. 2 is a front elevation of the device shown in Fig. 1, the interrupter being closed in Fig. 1 and open in Fig. 2.

Referring to the drawings, the device here 30 shown comprises a slab or base 1 of insulating material, a stationary contact member 2, secured to the base, and a movable contact member 3 carried by an arm 4 that is pivotally supported upon the base. A bifurcated end of the arm 4 is mounted upon a pin 5 with which a terminal member 6 is provided. The outer end of the arm 4 is enlarged and is recessed to receive the contact member 3. A handle 7 is secured to a projection 8 at the free end of the lever and constitutes a convenient means for manipulating the circuit interrupter.

Any suitable yielding connection may be 45 established between the contact member 3 and the arm 4, the contact member being provided, as shown, with a rod 9 which extends through a hole 10 in the enlargement 11 of the arm, and is provided with nuts 12 50 which prevent the contact member from being entirely separated from the arm. As already pointed out, the enlargement is bored out to form a recess 13 in which is located a helical spring 14.

The arrangement of parts is such that 55

the spring 14 tends to throw the contact member 3 out of the recess in the arm, this action being prevented by the nuts 12. The contact members 2 and 3 coöperate with each other and, when they are brought forcibly into engagement, the spring 14 is compressed and tends to swing the arm outwardly. In order to hold the arm in such position that the contact members are held in engagement with each other under pressure, I mount a magnetizable ring segment 15 on the enlargement 11 of the lever so as to partially inclose the contact member 3, and provide a coöperating magnetizable ring segment 16, upon a bracket or carrier 60 65 70 75 80 85 90 95 100 105 110

17 which surrounds the contact member 2. The arrangement of parts is such that the ring segments 15 and 16 are magnetized by the electric current that traverses the contact members 2 and 3 when the circuit interrupter is closed. The ring segments are so arranged that the magnetic circuit through them is only complete when they are in engagement with each other and, consequently, there is considerable magnetic attraction between them as long as normal current is flowing through the contact members.

By properly proportioning and designing the interrupter, the magnetic attraction 85 between the ring segments under normal conditions will hold the interrupter closed in opposition to the spring 14. The spring will obviously throw the interrupter to its open position whenever the voltage fails or 90 when the current falls below a predetermined amount.

The contact member 3 is closely fitted into the hole 10, and, consequently, it is 95 preferably connected to the arm 4 by means of a flexible shunt 18.

While I have illustrated a specific structure, I do not wish to be restricted thereto, and I desire that the scope of my invention shall only be limited by the appended 100 claims.

I claim as my invention:

1. A circuit interrupter comprising relatively movable contact members and coöperating magnetizable members severally attached to the respective contact members and jointly surrounding said members to form an electromagnet for magnetically holding said contact members together.

2. A circuit interrupter comprising rela-

tively movable contact members and coöperating magnetizable members severally attached to the respective contact members and jointly surrounding the said members 5 to be energized by the passage of current therethrough for magnetically holding the contact members together.

3. A circuit interrupter comprising a stationary contact member partially surrounded by a stationary magnetizable ring segment, a movable contact member, a second magnetizable ring segment associated therewith and coöperating with the first named segment to form a closed magnetic 10 circuit and means tending to separate the contact members in opposition to the attraction between the magnetizable members.

4. A circuit interrupter comprising a stationary contact member, a stationary ring 15 segment of magnetizable material partially surrounding the contact member, a movable contact member coöperating with the stationary contact member, a second magnetizable ring segment partially surrounding the 20 movable contact member and means tending to separate the contact members, said ring segments being disposed to form a closed magnetic circuit and serving to hold the contact members together.

5. A circuit interrupter comprising a stationary contact member, a pivotally supported and movable contact-bearing arm, co- 25 operating magnetizable members respectively associated with the contact members and combined to surround said members for magnetization by the current passing therethrough to prevent the separation of the con-

tact members, and a spring interposed between the movable contact members and the contact-bearing arm for exerting a pressure 40 between the contact members when the interrupter is closed.

6. A circuit interrupter, comprising relatively movable contact members, and means attached to said contact members and encircling the same when the interrupter is closed for holding the members together by the direct action of the magnetism developed in said means.

7. A circuit interrupter, comprising relatively movable contact members, and a plurality of magnetizable ring segments attached thereto and respectively partially surrounding said contact members, said segments being oppositely disposed and adapted to partially overlap when the interrupter is closed.

8. A circuit interrupter, comprising relatively movable contact members, a plurality of magnetizable members severally partially surrounding and attached to the respective contact members and adapted to form an encircling link of magnetizable material when the interrupter is closed for holding the members together directly by 60 the magnetism developed therein.

In testimony whereof, I have hereunto subscribed my name this 12th day of Dec., 1911.

FLETCHER D. HALLOCK.
